UNITED STATES PATENT OFFICE.

ALFRED JOHNSON, ARTHUR C. SWANSON, AND ALFRED H. UTTERBERG, OF CHICAGO,
ILLINOIS.

AUTOMATIC PLAYING ATTACHMENT FOR PIANOS.

1,307,052.

Specification of Letters Patent. Patented June 17, 1919.

Application filed June 21, 1916. Serial No. 104,850.

To all whom it may concern:

Be it known that we, ALFRED JOHNSON and ARTHUR C. SWANSON, both citizens of the United States, and ALFRED H. UTTERBERG, a subject of the King of Sweden, residents of Chicago, in the county of Cook and State of Illinois, have invented certain new and useful Improvements in Automatic Playing Attachments for Pianos, of which 10 the following is a specification.

Our invention relates to automatic playing attachments for pianos and particularly to details of simplified construction and arrangement for increasing the efficiency 15 with reduced cost of manufacture.

One of the features of our invention is simplified construction for the pneumatic key actuating structures, the construction involving a minimum number of simple 20 parts easily assembled or taken apart. Another feature of the invention resides in simplified and more practical connection between the pneumatics and the striker rods which enables the rods to be readily applied 25 and disconnected and which yieldingly and noiselessly holds the rods in place during playing. Another feature of the invention resides in an improved vacuum chest in the form of a continuous one-piece board 30 routed out and apertured to form vacuum compartments and connections thereof with the pneumatic key actuating structures. Another feature of the invention resides in the simplified arrangement for supporting 35 the pneumatic key actuating structures on the vacuum chest and connecting them with the vacuum compartments and ducts leading to the tracker board hose connections. The arrangement is such that by loosening one 40 screw a set of pneumatic key actuating structures are released and can readily be withdrawn.

The above enumerated features and others are embodied in the structure shown on the 45 accompanying drawings, in which drawings

Figure 1 is a plan view with parts broken away to more clearly reveal the construction and arrangement,

Fig. 2 is a front elevational view of part 50 of the structure,

Fig. 3 is a sectional view on plane 3—3, Fig. 1,

Fig. 4 is a sectional view on plane 4—4, Fig. 3, and

Fig. 5 is a sectional view on plane 5—5, 55 Fig. 3.

The vacuum chest 10 is a continuous one-piece board routed out to form the main vacuum compartment 11 and the sets of 60 passageways 12 and 13 for extending the vacuum compartment to the ports or openings for communicating with the pneumatic key actuating structures. The board is secured to two end blocks 14 and 15 extending at right angles therefrom by means of 65 which the vacuum chest can be secured in a piano frame. Through the end block 14 is the passageway 16 which communicates with the exterior and with the hole 17 in the chest leading to the vacuum compartment 70 thereof. As best shown in Fig. 4, an annular slot 18 is cut into the end block 14 around the outer end of passageway 16 to leave the annular flange 19. Into this slot is inserted the end of a flexible conductor 20 75 preferably of rubber which intimately receives the flange 19 to make an air-tight connection, this conductor in practice leading to the main suction bellows.

In Fig. 3 the construction of the pneumatic key actuating structures P is shown. 80 Each structure comprises the rectangular valve box 21 having the forward extension 22. A plate 23 is hinged at its rear end to the bottom of the valve box at the rear edge 85 thereof and fabric 24 is secured thereto and to the box to form the well known bellows or pneumatic. The box 21 has the annular slot or passageway 25 around the platform 26, the space 27 being above the diaphragm 28 which is secured at its periphery to the outer rim of the platform, the platform being hollowed out to provide the atmosphere 90 space 29 below the diaphragm and the central pocket 30. Surrounding the upper end 95 of the space 27 is the depressed annular seat 31 for a metal valve seat disk 32, a sealing washer 33 being preferably applied between the disk and seat. This disk has the opening 34 concentric with the diaphragm, 100 and for controlling said opening a valve disk 35 is provided. This disk is at its lower surface faced by leather 36 and its top faced with leather 37. The valve disk

35 has the axial hole 38 therethrough for receiving a screw 39, the upper part of the hole being countersunk to receive the correspondingly shaped head of the screw. The 5 threaded end of the screw is secured in a block 40 of substantially three-sided cross-section with the sides concave, as shown in Fig. 1, the opening 34 being sufficiently large to allow the block to project upwardly there-
 10 through. Between the valve disk and the block yielding washers 41 are inserted and the screw fits loosely in the hole through the valve disk so that the disk and block may readily tilt relatively. Secured centrally 15 and on the upper face of the diaphragm 28 is a plate 42 for engaging with the lower end of the valve block in order that the valve block and the valve will be raised when the diaphragm is raised. When the dia-
 20 phragm is down the valve rests on the seating disk 32 and closes the opening 34 leading to the space 27 above the diaphragm.
 The top of the box 21 is formed by a cover 43 which is detachably secured by means of 25 screws 44, the lower end of the cover being preferably faced by leather 45. Concentric with the valve 35 the cover has the cylindrical valve chamber 46 from which a passage-
 30 way 47 extends rearwardly and connects with the port 48 extending downwardly through the box 21 and communicating with the interior of the bellows. Above the valve chamber 46 is the port 49, this port being normally open but being closed by the valve 35 when this valve is raised by the dia-
 35 phragm to open the port 34, the bellows being normally connected with atmosphere through the passageways 48 and 47 and the port 49.
 40 In the front end of the box 21 is the longitudinal duct 50 leading to the annular slot 25 and the space 27. Extending through this duct and radially through the platform 26 to the pocket 30 below the diaphragm is a
 45 tube 51, the tube extending a short distance outside of the duct 50. In the outer end of the duct 50 is secured the annular plug or bushing 52.
 Through the front wall 53 of the vacuum 50 chest 10 are the circular openings 54 for receiving the projecting ends of the bushings 52, this connection effecting communication between the vacuum compartments in the vacuum chest and the spaces within the valve 55 boxes above the diaphragms. To more thoroughly seal the connection between the chest and valve boxes the rear ends of the valve boxes are faced by leather 55. In the rear wall 56 of the vacuum chest vertical 60 channels 57 are bored in alignment with the openings 54 in the front wall, and secured in the rear wall are tubes 58, these tubes communicating with the channels 57 and extending through and a distance beyond 65 the openings 54 to telescopically receive the

outer ends of the tubes 51 extending from the valve boxes. To seal the joints between the tubes rubber sleeves 59 are secured at their inner ends to the tubes 51 and at their outer ends receive the tubes 58, as clearly 70 shown in Fig. 3.

On top of the vacuum chest a cover 60 is detachably secured by screws 61 and this cover has the channels 62 extending upwardly from its lower face and then for- 75 wardly therethrough with nipples 63 inserted in the front ends. The inner ends of the channels register with the various channels 57, and at intermediate point thimbles 64 are inserted in the cover to connect 80 the channels through small bleed openings 65 with the vacuum compartment 11. To seal the connection between the cover and chest leather 66 is preferably provided. Hose lengths 67 connected with the nipples 63 lead 85 to the tracker board 68 to communicate with the tracker board openings 69 over which the music sheet 70 travels in practice.

Normally the diaphragm of each pneumatic key actuating structure is down and 90 the valve 35 opens the bellows to atmosphere through port 49 and disconnects the bellows from the space above the dia-
 phragm, there being vacuum above the dia-
 phragm by virtue of duct 50 and also vacuum 95 below the diaphragm by virtue of bleed opening 65, the channels 57 and the tubes 58 and 51. As a music sheet travels along the tracker board its openings come into register 100 with the tracker board openings and then through the channels 62 and 57 and the tubes 58 and 51 atmosphere is admitted into the space below the diaphragm and the dia-
 phragm is thrown upwardly to shift the valve 35 to close the atmosphere inlet 49 to the bel- 105 lows and to connect the bellows with the vacuum compartment in the vacuum chest, and the bellows plate 23 is drawn upwardly. On account of the triangular cross-section of the valve block 40 the air can readily flow 110 through the port 34 when the block extends therethrough. As soon as the tracker board opening is again closed the suction becomes effective at the lower side of the diaphragm through the bleed opening 65 and the 115 diaphragm is quickly pulled downwardly to disconnect the bellows from vacuum and re-
 connect it with atmosphere and the bellows plate will then drop.

The pneumatic key actuating structures 120 are secured to the valve chest in three rows, the structures of each row half-way over-
 lapping those of the row below. The bel-
 lows of each row are also separated a dis-
 tance to provide space for clamping rods 71 125 which are secured to the vacuum chest and extend rearwardly therefrom. Each rod ex-
 tends at its end through the center of the cross plate 72 and threadedly receives a nut 73. Each cross plate engages against the 130

5 rear ends of adjacent valve boxes 21, the rear ends of the boxes having preferably the grooves 74 for receiving and confining the plates. With this arrangement the pneumatic key actuating structures are readily accessible from the rear of the piano, and by inserting a screw driver between the structures the nuts 73 can readily be reached and turned to release the plates 72 or to secure 10 them against the structures.

15 As shown in the drawings the vacuum chest is placed in front of the piano action upright rods with the bellows extending rearwardly. Secured to and projecting 20 rearwardly from each bellows plate 23 is a shelf 75 having a slot 76 cut longitudinally therein from its outer end. Secured to the shelf above and below the inner end of the slot are the upper and lower leather disks 77 25 and 78 provided with the holes 79 and 80 from which entrance slits 81 and 82 respectively extend radially rearwardly in line with the arm slot 76, the holes in the washers being concentric with the semi-circular inner 30 end of the slot. At the end of the extension 35 22 of each valve box a guide bracket 83 is provided having the guide passageway 84 therethrough for the striker rod 85, the striker rod having the head 86 for engaging 40 with the under side of a head 87 adjustably secured by means of a threaded stem 88 in 45 the extension 89 extending from the upright rod 90 of the piano action. At its lower end each rod 85 has a screw 91 secured 50 axially therein a distance, the projecting shank of the screw passing through the holes 79 and 80 of the disks 77 and 78 and through 55 the slot 76 of the bellows arm 75. The holes 84 in the brackets 83 are preferably lined 60 with the yielding material 92 such as felt or leather, and the lower ends of the heads 86 are preferably provided with a facing 93 of leather or felt. The openings 84 are also 65 preferably of larger diameter than the rods 85 so that the rods can be swung laterally a 70 considerable distance. With this arrangement a rod can readily be removed from its connection with the bellows bottom by pulling on its lower end to draw the screw 91 75 through the slits 81 and 82 of the leather disks. Likewise, a rod can be readily reconnected by pushing the screw inwardly 80 through the slits, and after such insertion the slits close themselves and yieldingly lock 85 the rod to the bellows. The projecting end 90 of the screw is preferably of a length to cause the bottom of the rod and the head of the screw to always abut against the upper and lower disks respectively. On account 95 of the soft leather disks this will produce a yielding and flexible connection but one which has no lost motion and which is therefore noiseless. Instead of providing a single bracket 83 on each valve box, a continuous bracket may extend full length of

the valve box rows and be secured here and there to the boxes of the top row. Shorter lengths of bracket could also be used to guide the striker rods of a number of pneumatic key actuating structures.

70

When pneumatic key actuating structures are to be removed for inspection or repairs the corresponding striker rods are disconnected and raised out of the way and then when the corresponding nut 73 is withdrawn 75 and the clamping plate 74 released, the structures can be pulled away from the vacuum chest. When a structure is to be replaced its tube 51 is inserted into the corresponding tube 58 and the rubber sleeve 59 80 is engaged over the tube 58 and the bushing 52 is inserted in the corresponding opening 54, and then when the clamping plate 74 is applied and the nut 73 screwed onto the corresponding rod 71, the pneumatic key 85 actuating structure will be forced against the back of the vacuum chest and accurate connection is established. After securing of the key actuating structures the corresponding striker rods are lowered and re-connected 90 at their lower ends with the bellows bottom. The striker rods could, of course, engage with the piano action at different places. As shown in the drawings, the rods engage 95 with the abutments on the vertical rods 90 95 of the piano action but the player attachment could be positioned within the piano casing to bring the striker rods below the rear ends of the keys.

We thus produce a pneumatic playing attachment which comprises a minimum of parts and is therefore of very simple and inexpensive construction. This reduction in parts also increases the playing efficiency. The single piece vacuum chest body is a decided improvement over prior art constructions in which the vacuum chest is constructed of numerous parts. Furthermore, by having the vacuum chest body of a single piece it is of greater strength and affords better 105 110 and more rigid support for the pneumatic key actuating structures and keeps the striker rods at all times in perfect alignment with the piano action members to be engaged. The simple construction of the pneumatic key 115 actuating structures with the number of parts reduced to a minimum increases their efficiency, they being very quick to respond and there being no lost motion.

We do not, of course, desire to be limited 120 to the exact construction and arrangement herein shown and described as changes and modifications are no doubt possible which would still come within the scope of the invention.

125 We claim as follows:

1. In pneumatic playing mechanism for pianos, the combination of a vacuum chest having a vacuum compartment, valve boxes, openings in said chest communicating 130

with the vacuum compartment, vacuum ducts in said valve boxes, sleeves for holding said ducts in alinement with said openings, said chest having atmosphere channels, said valve boxes having atmosphere spaces, and connections extending from said atmosphere channels through said openings and into said atmosphere spaces.

2. In pneumatic playing mechanism for

10 pianos, the combination of a vacuum chest having a vacuum compartment, valve boxes secured with their ends against a face of said chest, a valve and an actuating diaphragm therefor in each valve box, there being space 15 above and below said diaphragm, a duct in each valve box communicating with the space above the diaphragm, openings to the vacuum compartment of said vacuum chest, bushings for alining said openings with said valve 20 box ducts, said chest having atmosphere channels, tubes extending from said channels through said openings, and tubes extending from the spaces below the diaphragms for telescoping into said first-mentioned tubes.

3. In pneumatic playing mechanism for pianos, the combination of a vacuum chest having a vacuum compartment, valve boxes secured with their ends against a face of said 30 chest, a valve and an actuating diaphragm therefor in each valve box, there being space above and below said diaphragm, a duct in each valve box communicating with the space above the diaphragm, openings to the 35 vacuum compartment of said vacuum chest, bushings for alining said openings with said valve box ducts, said chest having atmosphere channels, tubes extending from said channels through said openings, tubes extending from the spaces below the diaphragms for telescoping into said first-mentioned tubes, and a flexible sealing sleeve surrounding the junctures of said tubes.

4. In pneumatic playing mechanism for 45 pianos, the combination of a vacuum chest having a vacuum compartment, a valve box secured with its end against a face of said chest, a vacuum duct leading from the end of said box to the interior of said box, a bushing extending from said vacuum duct, said vacu-

um chest having an opening for receiving said bushing whereby to aline the box with reference to the chest, an atmosphere tube extending from the box through said bushing, said chest having an atmosphere channel, and a tube extending from said atmosphere channel through said opening for telescopically receiving the atmosphere tube of said box.

5. In pneumatic playing mechanism for 60 pianos, the combination of a vacuum chest having a vacuum compartment and an opening leading therefrom, said chest having an atmosphere channel, a tube leading from said atmosphere channel in line with said 65 opening, a valve box having a vacuum duct terminating at its end for communicating with said opening, and a tube extending from said box through said vacuum for communicating with said atmosphere tube in the 70 chest.

6. In pneumatic playing mechanism for pianos, the combination of a vacuum chest having a vacuum compartment and an opening 75 leading therefrom, an atmosphere channel in said chest and a tube extending therefrom into said opening, a valve box having a vacuum 80 duct and an atmosphere inlet, and means for securing said box to said chest with its vacuum duct and atmosphere inlet in communication respectively with said opening and said tube.

7. In pneumatic playing mechanism for pianos, the combination of a vacuum chest having a vacuum compartment and an opening 85 leading therefrom and having an atmosphere channel, a valve box having a vacuum duct and an atmosphere chamber, a tube extending from said valve box atmosphere chamber through the valve box vacuum duct, and 90 means for securing said box to said chest with the vacuum duct of the box in communication with the vacuum chest opening and with said tube in communication with the atmosphere chamber.

In witness whereof we hereunto subscribe our names this 17th day of June, A. D. 1916.

ALFRED JOHNSON.

ARTHUR C. SWANSON.
